R. ROYAL

COIN CONTROLLED MECHANISM

Filed Dec. 30, 1920

FIG. 1

FIG. 2

INVENTOR.

Roger Royal

UNITED STATES PATENT OFFICE.

ROSCOE ROYAL, OF CHICAGO, ILLINOIS.

COIN-CONTROLLED MECHANISM.

Application filed December 30, 1920. Serial No. 434,032.

To all whom it may concern:

Be it known that I, ROSCOE ROYAL, a citizen of the United States, residing at Chicago, county of Cook, and State of Illinois, 5 have invented new and useful Improvements in Coin-Controlled Mechanism, of which the following is a specification.

My invention relates to coin controlled mechanism in which forcing a coin through 10 the coin slot assists the parts in closing an electric circuit for driving an electric motor such as a fan motor when a predetermined number of revolutions of the shaft of the motor will in turn be assisted by suitable 15 gearing to open the electric circuit in restoring the coin mechanism to normal.

The object of my invention is: (a) to furnish an improved means of collecting a coin for use of an electric fan for a predetermined time or number of revolutions of fan; (b) to provide for collecting a number of coins successively at one time for extended use of the aforesaid fan motor for 25 a multiple of the predetermined time in accordance with the number of coins dropped up to a given limit, say ten; and (c) not to register further coins till part or all of the predetermined time has been worked out.

30 A form in which my invention may be practiced is illustrated in the accompanying drawings in which Fig. 1 represents a general working outlay of the parts. Fig. 2 shows an arrangement of parts to close the 35 circuit of the motor.

Referring to Fig. 1: 4 represents the frame of the coin box, 3 represents the frame of the gear casing at the motor shaft, 6 represents a flexible shaft or wire and its flexible housing 7 running between the two frames. Conductors 8 and 9 to complete the circuit of motor M also are shown running to the coin box. At V is shown the last deposited coin in place. The form of 45 coin box I have preferred to illustrate is such that the last coin deposited is held in place for view as to quality if desired—the preceding coin in each instance being used to operate the circuit closer by the aid of 50 the succeeding coin as will be shown. At P is a push button projecting through the top of the box normally held upward by rod 14 working through slot 17 and pressure of spring 15 against stop 16. Push button P is arranged to be pushed downward

the length of the coin used so when the first coin is passed through slot S into continuation of slot T it will drop as far as permitted by spring 45. Application of pressure from push button P will force the coin past 60 spring 45 into position at V ready to engage with projecting arm 19. As before mentioned, one coin is retained in the coin box so the mechanism is operated not by the first coin but by every coin thereafter. The 65 next coin dropped in slot S represented dotted at 5 will obviously when forced downward by push button P transmit a downward movement to coin V which in passing to coin box will momentarily push the lower 70 end of projecting arm 19 aside from obstructing the coin slot T. The arm 19 pivoted to the frame 4 at 20 and coupled at its upper end to arm 23 carrying the tooth 24 will when moved against tension of spring 22 out of normal position with lower end 75 obstructing the coin slot T, change the position momentarily of the arm 19, arm 23 and tooth 24 resting against stop 25 to locations represented by dotted lines so that tooth 24 is ready to engage a tooth of wheel 10. On forcing the coin V past the lower end of projecting arm 19 and into the coin box 47, arm 19 tends to return to normal, relieving the pull from arm 23 so spring 22 tending to retract arm 23 causes tooth 24 to engage a tooth of wheel 10 and move wheel 10 one tooth in direction of arrow, placing a succeeding tooth under lower pellet of escapement 26 under pressure of spring 27 and arm 23 and tooth 24 return to normal against stop 25. This same movement of wheel 10 moves insulation 31 attached thereto under spring 12 bringing it into contact with spring 11 closing the circuit of motor M 95 through rheostat R, conductor 9, spring 11, spring 12, conductor 8 to the mains.

The action of springs 11 and 12 in the circuit closing operation is also shown in Fig. 2.

As the motor runs, shaft 33 which is the motor shaft and carries the fan, revolves, turning screw 34 meshed with saw tooth wheel 35 running on pin 37 and carrying pinion 36 in mesh with wheel 38, revolving 105 on pin 44 carrying hub 39 and cam 40. These gear elements suitably reduce the motor speed. The cam 40 controls the circuit of the motor and causes this circuit to be broken after the motor has driven the 110

fan a predetermined interval. Pivoted to frame 3 at 43 is arm 41 pressing against hub 39 ready to engage with cam 40. At the upper end of arm 41 wire 6 is attached at 5 eyelet 42. At its further end wire 6 is attached to double escapement 26 by spring 28. Spring 29 applies tension to draw wheel 10 to normal. As wheel 38 revolves cam 40 is brought about to force arm 41 out- 10 ward, pulling wire 6 applying tension on spring 28 to pull upper pellet of 26 to engage with wheel 10, allowing the escapement of $\frac{1}{2}$ tooth by relieving the lower pellet from engagement with wheel 10. On 15 further revolution of wheel 38 the cam 40 allows arm 41 to return to rest against hub 39, allowing wire 6 to move back relieving tension on spring 28 which in turn allows spring 27 to draw back double escapement 20 26 relieving upper pellet thereon from engagement with wheel 10 and allowing the latter to drop back another half tooth. In this instance the wheel 10 is at normal, the projection 20 thereon touching stop pin 49. 25 The insulation 31 also moves from under spring 12, breaking the circuit of the motor.

It is obvious from the drawing that the wheel 10 may be advanced a reasonable number of steps by the use of successive coins 30 till the space 50 comes to double escapement 26 when no further advance will be possible regardless of how many coins are deposited.

I do not limit myself to the details as set forth in this description as many changes 35 could be made in the apparatus and arrangement without departing from the spirit of the invention.

From the description I claim:

1. The combination with a motor; of a worm wheel upon the motor shaft; a gear 40 train operated by the worm wheel and including a follower member; a lever escapement and ratchet member; and a flexible connection in controlling relation to said escapement and controlled by said follower 45 member.

2. The combination with an electric motor; of a switch in controlling relation to the motor circuit; ratchet and escapement mechanism governing said switch; and a flexible connection between the motor and the escapement and operable by the motor 50 to operate the escapement.

3. The combination with an electric motor; of a switch in controlling relation to the motor circuit; ratchet and escapement mechanism in actuating relation to said switch; a flexible connection between the motor and the escapement and operable by the motor to operate the escapement; and a pawl engageable with the teeth of the ratchet 55 and serving to operate the ratchet step by step.

4. The combination with an electric motor; of a switch in controlling relation to the motor circuit; ratchet and escapement mechanism in actuating relation to said switch; a connection between the motor and the escapement and operable by the motor 60 to operate the escapement; and a pawl engageable with the teeth of the ratchet and serving to operate the ratchet 65 step by step.

ROSCOE ROYAL.
